UNITED STATES PATENT OFFICE.

CHESTER D. AINSWORTH, OF WOLLASTON, MASSACHUSETTS, ASSIGNOR, BY MESNE ASSIGNMENTS, TO CONDIT ELECTRICAL MANUFACTURING CORPORATION, OF BOSTON, MASSACHUSETTS, A CORPORATION OF MASSACHUSETTS.

MOTOR-CONTROL SWITCH.

Application filed March 28, 1921. Serial No. 456,318.

This invention relates to electric switches especially adapted for the control of the motors of individually motor driven machines as looms, lathes, saws and the like.

Such machines are usually started and stopped many times a day and it is desirable to control them at the machine as by a shipper rod which may extend the length of the machine so that an operative positioned at any location adjacent the machine may start and stop it; or by other devices; or in a manner similar to the control of the machine when a belt drive from a power shaft is employed.

The motor is usually provided with a remotely controlled switch which may be of the type having separate closing and opening coils or a single closing coil adapted to be continually energized to hold the switch closed; or the switch may be otherwise arranged.

The remote control switch for the aforesaid switch usually has two push buttons, one for starting and the other for stopping the motor; and such control switches are usually located near the machine driven by the motor.

An object of this invention is the provision of a control switch having depressible switch members and mechanism by which to operate the switch.

A further object is to provide mechanism adapted to operate a push-button type electric switch.

A further object is to provide an oil immersed remote control switch for the motor control switch.

Briefly the switch embodying the invention may comprise a casing adapted to contain oil and switch operating mechanism above the oil. The switch elements are received in the casing and may be immersed in the oil. Cams are adapted to engage the push buttons or depressible switch members and a sliding bar is adapted to be operated to depress said cams, thereby to depress said depressible members, and operate the switch. A movement of said bar in one direction is adapted to operate the switch to stop the motor and a movement of said bar in the opposite direction is adapted to operate the switch to start the motor.

Fig. 1 is a vertical longitudinal section of a switch embodying the invention.

Fig. 2 is a transverse vertical section along line 2-2 of Fig. 1.

Fig. 3 is a plan section along line 3-3 of Fig. 2.

Fig. 4 is a detail similar to Fig. 3 but with some of the mechanism removed to expose the cams.

Fig. 5 is a plan detail similar to Fig. 4 but with the top cam guide and cams removed to expose the lower cam guide.

Fig. 6 is a sectional view of a cam.

Fig. 7 is a sectional detail illustrating the arrangement of the cams to operate a modified type of switch.

Fig. 8 is a sectional detail similar to Fig. 7 illustrating the cam arrangement for a further modified switch.

Fig. 9 is a side elevation, partly in section, of the switch equipped with pull cords for operating it.

Fig. 10 is a plan detail of a remote control switch arranged to control a motor switch having one operating coil.

Fig. 11 is a diagrammatic representation of the contact members of the switch of Fig. 10.

Fig. 12 is a diagrammatic representation of the contact members of a switch adapted to control a motor switch having two independent operating coils.

Fig. 13 is a diagrammatic representation of the contact members of a switch which in itself may directly control the motor.

Fig. 14 is a detail of a pin adapted to be interposed between a cam and a depressible switch member for certain purposes.

As here shown, the switch embodying the invention includes the casing having the front and rear walls 10^a and 10 and side walls 90 11 and 11^a. An attaching member 12, here shown as a flat plate, is secured to the rear wall and extends beyond the side walls; and the extended portions thereof may be provided with holes 13 through which bolts may be passed to secure the switch to a support. A cover 14 is adapted removably to close the top of the receptacle and the securing means for the cover may comprise the screws 15.

A receptacle 16 depends from and has its 100 top portion received within said casing; and said receptacle is removably secured thereto by the screws 17 and is adapted to contain oil in which the switch members are immersed.

The switch adapted to be received within

- the casing is characterized by having the body 18, usually of an insulating material, and the two push buttons or movable switch members 19 and 20 which rise above said body and may be yieldingly held in elevated position by the springs 21 which encircle them. Said body may also have the ears 22 extended from its opposite sides by which the switch may be secured within the casing.
- 10 The motor control switch adapted to be controlled by the aforesaid switch may be characterized by having a single coil which is adapted to be energized to hold the switch closed and be de-energized to open the switch.
- 15 The motor switch, also, may be of that type having a closing coil adapted to be momentarily energized to close the switch, and the switch will thereafter stay closed, and an opening coil adapted momentarily to be energized to open the switch.

For that type of motor switch having a single closing or holding coil one of said buttons, as 20, (see Fig. 11,) may be arranged to hold its circuit normally closed, and the other button, as 19, to hold its circuit normally open. Said button 20 may have a stem 20^a which bears a contact disc 20^b disposed beneath the two stationary contact members 23, and held in normal contact therewith by the spring 21. The button 19 may have a stem 19^a which bears a contact disc 19^b disposed normally above and free from contact with the stationary contact members 24. The depressing of button 20 may operate to open the circuit connected therewith and de-energize the holding coil of the motor control switch, thereby to stop the motor; and the depressing of button 19 may operate to close the circuit connected therewith to energize the holding coil, which may thereafter be held closed, thereby to close the motor switch and start the motor.

For that type of motor switch having independent opening and closing coils, a remote control switch having two circuit-closing units may be employed, as in Fig. 12. In this switch the button 20 may be associated with the stationary contact members 25 and the contact disc 20^b normally supported above and free from electrical contact with said members. The button 19 may have similar stationary contact members 26 and be similarly arranged.

The switch may also be as diagrammatically illustrated in Fig. 13 wherein the two push buttons 19 and 20 are connected to opposite ends of a lever 27 and button 20 is adapted to be depressed to move said lever into bridging engagement with the stationary contact members 28 and close the circuit; and said buttons 19 depressed to raise said lever and open the circuit. Said switch may, in itself, function directly as a motor control switch.

65 The switches diagrammatically illustrated

in Figs. 11, 12, and 13 are more or less standard switches, and the push buttons, without the operating mechanism hereinafter to be described, are adapted to be engaged and depressed by an operative to start or stop the machine controlled by it; and it is an object of this invention to employ such a switch, without substantial modification, with mechanism by which to operate it.

The mechanism for operating the switch 75 includes the cams or plungers 30 and 31 which are adapted to rest upon the push buttons 19 and 20 respectively; and said cam 30 may be adapted to be depressed to depress the button 19 to stop the motor; and said cam 80 31 may be adapted to be depressed to depress the button 20 to start the motor. Said cams, preferably, are identical and each is substantially rectangular in shape and of substantial thickness. Each cam has the flat top cam face *a* and the downwardly inclined cam faces *b* adapted to be engaged by a cam roller of operating mechanism hereinafter to be described and depressed to start and stop the motor.

Said cams are guided for vertical movement by the upper cam guide 32 and lower cam guide 33. Said upper guide is formed of a flat strip of metal having the downwardly reflexed end-portions 32^a which engage the side walls 11 of the casing and to which they are secured by the screws 34. Said lower guide also is formed of a flat strip of material and has its end-portions reflexed to form first the downwardly extended portions 33^a, then the outwardly extended portions 33^b which are parallel but below the body of the strip, and then the upwardly extended portions 33^c which engage the side walls of the casing and are secured thereto by the screws 35. Aligned rectangular apertures 36 and 36^a, and 37 and 37^a are formed in said guides 32 and 33 in which said cams 30 and 31 are slidably received. Each cam has a hole 38 therein in which cotter pins 39 are extended; and said cotter pins are adapted to engage the under side of the top guide 32 to hold the cams in the guides against vertical displacement therefrom.

The ears 22 of the switch assembly are secured removably to the portions 33^b of the lower guide 33 by the screws 40; and a plate 41 may be interposed between said ears and the portions 33^b of the lower guide; and said plate may have apertures therein through which said push buttons 19 and 20 are extended by which said buttons are guided for vertical movement.

The operating mechanism for said cams comprises the two edgewise-arranged, closely-spaced bars 42 and 43 which extend through the casing above the cams and are slidably received in slots 44 and 45 in the opposite side walls 11 and 11^a of the casing. A pin 46 is passed through aligned apertures in the mid-

dle of said rods and is held in place by suitable means, as the cotter pin 47. A roller 48 is disposed on said pin between said bars and is adapted to engage and depress said cams 30 and 31 when said bars are moved from one to the other side in the casing thereby to operate the switch. Pins 49 are passed through aligned openings in the ends of said bars and are adapted to connect said bars, 10 at either, or both, ends, with operating devices, as a shipper rod, not shown, and the like.

The push buttons or depressible switch members 19 and 20 of the switch assembly 15 may be of unequal height as indicated in Figs. 1 and 7; and usually the motor start button 20 is higher than the motor stop button 19, for reasons herein unnecessary to enumerate. For these reasons the lower end portions of 20 said cams are formed with the projections *c* which extend below the face *d*. For some purposes the face *d* of the cam is adapted to be disposed over a push button, and for other purposes the projection *c* is adapted to be 25 disposed over a push button. In Fig. 1, for instance, the projections *c* are over both push buttons while in Fig. 7, the projection *c* is over the push button 19 while the face *d* is over the push button 20 and in Fig. 8 the 30 faces *d* of both cams are over both push buttons.

To ensure a good electrical contact between the stationary contact members and the bridging member carried by a push button, 35 as when the push button controls a circuit closing switch as illustrated in the left hand switch of Fig. 11 and both switches of Fig. 12, and also to provide for slight inaccuracies in machining and assembling the switches 40 and operating mechanism, resilient means may be interposed between the cams and the push buttons to permit further downward movement of the cams under control of the cam roller 48 after the push buttons have been 45 moved into extreme depressed positions. Said means may comprise the pin 50 having the enlarged head 51 which is adapted to rest upon the top of a push button. Said pin is adapted to be slidably received in said holes 50 52 and 53 extended into the body of the cam from the face *d* and from the face of the projection *c*. A spring 54 encircles said pin 50 and engages the cam and the head 51 and tends to maintain said pin in extended position. It will be seen that after a push button, 55 as 19, has moved its bridging disc 19^b into contact with the stationary contact members 24 and further movement of said button is prevented, the cam may yet be moved downward by compressing the spring 54. For a 60 switch assembly having a circuit opening-switch, as the switch controlled by the push button 20, Figs. 1 and 11, the pin 50 and spring 54 may be omitted as the downward movement of said push button, under control

of the cam roller 48, is not restricted. Consequently, in Fig. 1, said pin will be applied only to the cam 30 which controls the circuit closing or motor-start button 19. In Fig. 7, however, where both push buttons control 70 circuit closing switches, as diagrammatically illustrated in Fig. 12, each cam may have the interposed pin 50 and spring 54. In Fig. 8 the switch mechanism, in itself, may permit a substantial movement of the push buttons 75 beyond the points at which the circuit is closed or made and consequently the interposed resilient means will be unnecessary.

A further feature of the invention resides in a separate compartment contained in the 80 casing in which the switch leads and conduit leads are connected and stowed, and thereby held from contact with the switch operating mechanism and with the oil in the switch. Said compartment A is disposed at the rear 85 of the operating mechanism and above the oil in the casing and has its front walls 60 and bottom wall 61 formed of a single L-shaped sheet of material having the reflexed ears 62 and 63 which engage and are fixed to 90 the side walls of the casing by suitable means, as spot welding. The rear wall 10^a of the casing is adapted to form the rear wall of the compartment. A side wall 11^a of the casing, at the back part thereof may be provided 95 with an opening therethrough adapted to receive a conduit 64 which may communicate with said compartment A; and the bottom wall 61 of said compartment has an aperture 100 in which the bushing 65 is received by which communication between the compartment and the interior of the switch casing is established. Switch leads 66 are connected with the switch terminals and are extended through the bushing 65 into the compartment 105 for connection with leads 67 of the conduit 64. Preferably said switch leads are insulated with an insulating material unaffected by the oil in the casing. The conduit leads 110 are usually insulated with rubber or other material which may be affected by the oil, and the insulation of the conduit leads would soon become destroyed if extended directly to the switch terminals.

For some purposes it is desirable to locate 115 the switch in an elevated position above the machine adapted to be controlled by the switch, and drop control cords from the switch to a convenient position to be grasped and operated by the machine operative. Fig. 120 9 illustrates the switch adapted for this purpose. As here shown, brackets 70 are attached to each side of the switch casing by the screws 34 and 35. Bell crank levers 71 are pivoted to said brackets and the ends of 125 the arms 71^a thereof have the elongated slots 72 therein through which the pins 49 carried by the ends of the bars 42 and 43 are extended. Rods or cords 73 are connected with the other arms 71^b which may terminate in han- 130

dles, not shown, by which the cords may readily be grasped by the operative.

To operate the switch to start or stop the motor the bars 42 and 43 bearing the cam roller 48 are moved from one to the other side in the casing. In Fig. 1 the switch has been operated, say, to stop the motor. To start the motor the bars are moved to the left to carry the cam roller 48 over and depress both cams 31 and 30 in successive order. The depression of cam 31 and the push button 20 to open the circuit controlled thereby will be without effect as said circuit will stand open at the motor switch. The subsequent depression of the cam 30 and the push button 19 operates to close the circuit for the closing coil of the motor switch and the motor switch closes and the control of the closing coil is thereby shifted to the push button 20 in a well known manner. To open the motor switch and stop the motor the bars 42 and 43 are moved over the cams in the reverse direction and the final depression of cam 31 and the push button 20 operates to break the closing or holding coil circuit, whereby the motor switch will open. Usually the last push button to be operated by the cam roller determines the starting or stopping of the motor.

It will be noted that, excepting the switch illustrated in Figs. 8 and 13, the push buttons are but momentarily depressed yet the period of depression is sufficient to control the motor in the manner desired.

It is obvious that the invention may be embodied in variously modified structures without departing from the spirit thereof.

I claim:

1. An electric switch comprising a switch assembly having self-supported depressible switch-operating members, a support located above said depressible members, and operating mechanism having independently operable plungers slidable in said support above and arranged to depress said depressible members one at a time.

2. An electric switch comprising an enclosing casing having a lower removable receptacle adapted to contain oil, a switch assembly disposed within said casing and immersed in the oil having self-supported depressible switch-operating members, and operating mechanism disposed within said casing and above the oil therein having independently operable cam members one at a time engageable each with a depressible member and movable in the direction of movement of said depressible members, thereby to depress them.

3. An electric switch comprising an enclosing casing having a lower removable receptacle adapted to contain oil, a switch assembly disposed within said casing having depressible switch-operating members, and operating mechanism engageable with said depressible members disposed within said

casing including a rectilinearly movable member extended without said casing adapted to be moved back and forth to operate the operating mechanism, and means actuated by said member arranged to actuate said depressible members in succession. 70

4. An electric switch comprising a supporting base, movable and stationary contact members carried thereby, independently movable depressible members carried by said base adapted to be depressed to operate the switch, resilient means to raise said depressible members subsequent to their depression, a receptacle adapted to contain oil in which said switch is immersed, and means to actuate 80 said depressible members in succession. 75

5. An electric switch comprising a supporting base, movable and stationary contact members carried thereby, depressible switch members associated with said movable contact members adapted to be depressed to operate the switch, and operating mechanism arranged to depress said depressible switch members, said operating mechanism including an independently movable depressible operating member for each depressible switch member, and an actuating member arranged independently to engage and depress said 90 depressible operating members one at a time. 85

6. An electric switch comprising an enclosing casing, a switch assembly disposed within said casing having depressible switch members, and operating mechanism disposed within said casing arranged to depress said 95 depressible switch members, said operating mechanism including an independently depressible operating member for each depressible switch member, and an actuating member arranged independently to engage and depress said 100 depressible operating members 105 one at a time.

7. An electric switch comprising a supporting base, sets of movable and stationary contact members carried thereby, a depressible member for each set of contact members carried by said base adapted to be depressed to operate the switch, means to return said depressible members to raised position subsequent to their depression, a receptacle adapted to contain oil in which said switch is immersed, a reciprocable operating member, and means carried by said member arranged to actuate said depressible members one at a time. 110

8. An electric switch having two depressible switch members both arranged to be depressed to control circuits, two cam members each separately engageable with a depressible switch member, and operating mechanism arranged successively to depress and release 115 said cam members whereby successively to depress and release said depressible switch members. 120

9. An electric switch having two depressible switch members, an independently oper- 130

able cam member engageable with each switch member, and operating mechanism arranged successively to depress and release said cam members whereby to depress and release said switch members successively, and raising means for said switch members arranged also to raise said cam members upon the release thereof by said operating mechanism.

10. An electric switch having a depressible circuit-closing switch member and a depressible circuit-opening switch member, an independently operable depressible cam member disposed above each switch member, and means disposed above said cam members movable to depress said cam and switch members in succession.

11. An electric switch having a depressible circuit-closing switch member and a depressible circuit-opening switch member, an independently depressible cam member disposed above each switch member, and means disposed above said cam members operable to depress said cam and switch members successively by a movement in one direction.

12. An electric switch having two depressible switch members, a cam disposed above each member to operate it, and a switch operating bar disposed above said cams having means to engage and ride over said cams successively whereby to depress them and said switch members.

13. An electric switch having two depressible switch members, a cam disposed above each member to operate it, and a rectilinearly movable bar disposed above said cams having a cam roller engageable with said cams to depress them and said switch members successively.

14. An electric switch having two depressible switch members, a cam disposed above each member to operate it, and a rectilinearly movable bar disposed above said cams having means to engage and ride over said cams successively whereby to depress them and said switch members and means to raise said switch members and cams after depression.

15. An electric switch having two vertically movable depressible switch members, and operating mechanism for said members including an operating bar transversely rectilinearly movably disposed above said switch members adapted to depress them successively, and means to guide said bar for rectilinear movement only.

16. An electric switch having an enclosing casing, two depressible switch members disposed therein, cam guides disposed above said switch members, cam members vertically movably received in said guides above said switch members and having free upper ends disposed above said guides, and a switch operating bar slidably mounted above the free ends of said cam members in said casing and having means to engage and ride upon said free ends.

17. An electric switch having an enclosing casing, two depressible switch members disposed therein, cam guides disposed above said switch members, cam members vertically movably received in said guides above said switch members and having free upper ends disposed above said guides, a switch operating bar slidably mounted in the side walls of said casing having means to engage and ride upon said free ends and also having an end extended beyond the casing adapted to be moved rectilinearly to depress said cams and switch members.

18. An electric switch having an enclosing casing, two depressible switch members disposed therein, cam guides comprising two vertically-spaced strips having aligned cam openings disposed above said switch members and secured to the side walls of said casing, cam blocks slidably received in the openings in said guides and resting upon said switch members and extended above said top guide, two connected spaced parallel bars slidably received in slots in opposite walls of said casing above said cams and extended outwardly beyond said side walls, and a roller carried between said bars engageable with said cam-blocks to depress them and thereby depress said switch members.

19. An electric switch having a depressible switch member, a cam member for operating said depressible switch member having an aperture in it, a pin slidably received removably in said aperture having an enlarged head portion engageable with said switch member, and a spring interposed between said pin and cam.

20. An electric switch having two depressible switch members, cam guides having rectangular cam receiving apertures disposed in horizontal alignment above said switch members, rectangular cam blocks slidably received in said guide-apertures and engageable with said switch members and an operating bar disposed for horizontal movement above said cam blocks having means to engage and actuate said blocks successively.

21. An electric switch having a depressible switch member, a cam guide, and a cam-member slidably disposed in said guide arranged to depress said switch member, said cam-member having a lower face and a projecting portion extended beyond the lower face each adapted to engage selectively the switch member by reversing said cam member in said cam guide.

22. An electric switch having an enclosing casing, cam guides comprising two vertically spaced strips having reflexed ends secured to opposite side walls of said casing, said strips having vertically aligned cam slots therein, cam members slidably received in said slots and extended above and below the guides, a switch operating bar slidably disposed in slots in the opposite side walls of said casing

above said cam members arranged to engage and depress said cam members, and a switch assembly secured to the lower cam guide having two depressible switch members disposed beneath said cam members.

23. An electric switch having an enclosing casing adapted to contain oil, switch members and operating mechanism disposed therein, said operating mechanism including an operating member extended outwardly through a side wall of the casing, a side compartment within the casing above the oil therein free from switch members and operating mechanism having an aperture in its bottom wall through which switch leads may be extended to connect with the switch members, and having an aperture in its side wall through which circuit leads may be extended to connect with the switch leads therein and a cover which forms a closure for said casing and also for said compartment.

24. An electric switch including two spaced depressible switch-operating members, a cam guide disposed above said depressible members and having approximately rectangular apertures therein disposed above said depressible members, and separate and rectangular cam blocks received loosely in said apertures with their long dimensions in approximate

alignment and disposed loosely upon said depressible members, and an operating bar disposed above and in line with said cam blocks and having means to engage and ride over said cam blocks, and means to guide said operating bar for rectilinear movement over said cam blocks.

25. An electric switch including two spaced depressible switch-operating members, a cam guide disposed above said depressible members and having approximately rectangular apertures therein disposed above said depressible members, and separate and rectangular cam blocks received loosely in said apertures with their long dimensions in approximate alignment and disposed loosely upon said depressible members, said cam blocks having stepped faces at their lower ends arranged for selective engagement with said depressible members, and an operating bar disposed above and in line with said cam blocks and having means to engage and ride over said cam blocks, and means to guide said operating bar for rectilinear movement over said cam blocks.

In testimony whereof, I have signed my name to this specification.

CHESTER D. AINSWORTH.
